UNITED STATES PATENT OFFICE.

HOWARD A. KEHL, OF NORTHPORT, MICHIGAN.

PEN-EJECTING HOLDER.

1,090,862.

Specification of Letters Patent.

Patented Mar. 24, 1914.

Application filed May 23, 1913. Serial No. 769,480.

To all whom it may concern:

Be it known that I, HOWARD A. KEHL, a citizen of the United States, residing at Northport, in the county of Leelanau and State of Michigan, have invented certain new and useful Improvements in Pen-Ejecting Holders, of which the following is a specification, reference being had therein to the accompanying drawing.

10 This invention relates to pen holders and more particularly to that class of pen holders that are adapted to release the pen without the hands coming in contact with the pen.

15 The object of this invention is to provide a pen holder of the above description that will securely hold the pen in the holder and will discharge the pen by merely pressing a lever head or button.

20 Another object of this invention is to provide an improved means for holding the coil spring used in connection with this invention.

25 With these and other objects in view this invention consists of certain novel combinations, constructions and arrangements of parts as will be hereinafter fully described and claimed.

30 In the accompanying drawing: Figure 1 is a longitudinal section of my improved pen holder showing a pen in position. Fig. 2 is a longitudinal section showing a pen discharged from the holder. Fig. 3 is a section taken on line 3—3 of Fig. 1. Fig. 4 is a section taken on line 4—4 of Fig. 1. Fig. 5 is a perspective view of the spring holding means. Fig. 6 is a perspective view of the spring holding means showing the downwardly bent fingers in engagement with one

40 end of the spring. Fig. 7 is a plan view of the blank from which the spring supporting means is formed. Fig. 8 is a perspective view of the spring used in connection with the locking lever. Fig. 9 is a plan view of a pen with the engaging aperture formed therein.

45 Referring to the parts by reference numerals: 10 denotes the body of the pen holder having the cylindrical sleeve 11 mounted on one end, said cylindrical sleeve 11 provided with an opening 12 adjacent the end of the body 10. A pen guiding block 13 is secured in the opposite end of the sleeve 11 from that of the opening 12 and is provided with the pen guiding or receiving slot 14. Carried within the cylind-

rical sleeve 11 is an angle support 15 that has a securing foot 16 through which the securing means passes, and an upstanding portion 17 having an enlarged rounded head 18 at its upper end, said head 18 provided with a plurality of tongues 19. This member 15 is secured in the sleeve 11 intermediate the end of the body 10 and the inner face of the pen guiding block 13. A coil spring 20 is carried in the cylindrical sleeve by the angle supporting member 15 and one end of the coil spring 20 rests flatly against the enlarged rounded head 18 of the member 15, and the end of the spring secured thereto by means of the downwardly bent tongues 19. The opposite end of the coil spring 20 is adapted to be positioned against the substantially semi-circular pen engaging disk 21 thereby normally urging said disk outwardly. It will be seen by carefully observing Fig. 4 that this disk 21 is substantially semi-circular in shape and therefore is guided by the rounded sides of the sleeve 11. Pivotedly mounted on a pin 22 that is secured in this sleeve 11 is a locking lever 23 that comprises an upward and forwardly extending end 24 terminating in a downwardly projecting finger 25. The opposite end of the locking lever 23 is provided with an upwardly extending finger engaging member 26 that passes through the opening 12 in the sleeve 11. A flat spring 27 is secured to the sleeve 11 by the rivets 28 and is provided at its inner end with a plurality of upwardly extending ears 29 that are adapted to straddle the inner end of the locking lever 23, thereby forcing said inner end upwardly.

50 It will be understood that inasmuch as the pen has an aperture 30 formed adjacent its end that by inserting the pen in the slot 14 thereby pushing the disk 21 to the position as shown in Fig. 1, the downwardly extending finger 25 of the locking lever 23 will engage said opening in the pen and hold the same in a locked position inasmuch as the spring 27 will keep the finger in the opening. When it is wished to discharge the pen from the pen holder, all that is necessary is to press the member 26 thereby rocking the locking lever 23 which in turn moves the finger 25 from the opening 30 in the pen and the spring 20 will expand forcing the disk 21 against the inner face of the block 13, and thereby pushing the pen from the sleeve.

It is obvious that minor changes may be made in the form and construction of this invention without departing from the spirit thereof. It is therefore not wished to confine the invention to the exact form herein shown and described, but it is wished to include all such as properly come within the scope claimed.

Having thus described the invention, what is claimed as new, is:

10. A pen holder comprising a body, a sleeve carried thereby, pen guiding means carried by one end of said sleeve, a pen positioned in said guiding means and provided with an aperture adjacent one end, an angle support carried by said sleeve, said support provided with a plurality of downwardly bent tongues adapted to engage one end of the coil spring, the other end of said coil spring engaging a pen engaging disk to normally exert said pen engaging disk outwardly, and a lever engaging said pen for holding the same in said sleeve.
15. A pen holder comprising a body, a

sleeve carried thereby provided with an aperture adjacent the end of said body, pen guiding means carried by said sleeve, a pen positioned in said pen guiding means, said pen provided with an opening adjacent one end thereof, means for normally exerting 30 said pen outwardly, a lever pivotally mounted in said sleeve, comprising a body, a downwardly extending foot at one end of said body adapted to engage said opening in said pen, and an upwardly extending member 35 at the opposite end of said lever, said member passing through said opening in said sleeve and a spring carried by said sleeve provided with upwardly extending ears at its end, said ears adapted to straddle one 40 end of said lever for normally holding said lever in engagement with said pen.

In testimony whereof I hereunto affix my signature in presence of two witnesses.

HOWARD A. KEHL.
